UNITED STATES PATENT OFFICE.

HENRY L. GRASMUK, OF NEWARK, NEW JERSEY, ASSIGNOR TO KREMENTZ & CO., OF SAME PLACE.

DESIGN FOR A LORGNETTE-CASE.

SPECIFICATION forming part of Design No. 29,962, dated January 10, 1899.

Application filed December 17, 1898. Serial No. 699,611. Term of patent 3½ years.

To all whom it may concern:

Be it known that I, HENRY L. GRASMUK, a citizen of the United States, residing at Newark, in the county of Essex and State of New Jersey, have invented and produced a new and original Design for a Lorgnette-Case, of which the following is a specification, reference being had to the drawings accompanying and forming a part of the same.

Figure 1 is a plan view of the outside face of a case for a lorgnette. Fig. 2 is a section on the line *a a* of Fig. 1. Fig. 3 is a section on the line *b b* of Fig. 1.

The general form or outline of the design is that of the indent-spatulate order.

Referring to the drawings, A represents a body of the lorgnette-case, which is surrounded by the plane border B, dented at C and D. Within this border are located the knotted sprays of foliate scrolls E and F, which separately extend up the opposite edges of the body, joining together at the top thereof and including the scroll-shield G. This scroll

foliation is of perforated work. In other words, the spaces between the parts of the figures and the figures and the border and shield are perforations. At the top of the body is located the crest H, bearing dependent foliate decoration. The body-outlines merge into the perforated cup-capital I, which joins the spatulate-handle J, the end of which is dented at K and bears as surface decoration the perforate foliate knot L.

The essential feature of the design is the spatulate body and handle, together with the perforate surface decoration, the general motive of the design being that of pierced renaissance.

What is claimed as new is—

The design for the case of a lorgnette, substantially as shown and described.

HENRY L. GRASMUK.
